UNITED STATES PATENT OFFICE.

JOSEPH BERGE, OF DAYTON, OHIO, ASSIGNOR TO A C SPARK PLUG COMPANY, OF FLINT, MICHIGAN, A CORPORATION OF MICHIGAN.

DESIGN FOR A FACEPLATE FOR COMBINATION SPEEDOMETER AND ODOMETER OR SIMILAR ARTICLE.

Application filed May 16, 1921. Serial No. 470,013. Term of patent 14 years.

To all whom it may concern:

Be it known that I, JOSEPH BERGE, a citizen of the United States, residing at Dayton, in the county of Montgomery and State of Ohio, have invented a new, original, and ornamental Design for Faceplate for Combination Speedometer and Odometer or Similar Article, of which the following is a specification, reference being had to the accompanying drawing, forming part thereof.

The figure is a front elevation of a face plate for combination speedometer and odometer showing my new design.

I claim:

The ornamental design for a faceplate for combination speedometer and odometer or similar article, as shown.

In testimony whereof, I hereunto affix my signature.

JOSEPH BERGE.
